(57) **CLAIM**

The ornamental design for a slope adjustable head for pedestal jack, as shown and described.

DESCRIPTION

FIG. 1 is a top perspective view of the slope adjustable head for pedestal jack of the present invention;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top perspective view showing first and second components of the slope adjustable head for pedestal jack in a separated position;

FIG. 10 is a bottom perspective view thereof;

FIG. 11 is a top perspective view of the first component of the slope adjustable head for pedestal jack of the present invention;

FIG. 12 is a bottom perspective view thereof;

FIG. 13 is a top plan view thereof;

FIG. 14 is a bottom plan view thereof;

FIG. 15 is a front elevational view thereof;

FIG. 16 is a rear elevational view thereof;

FIG. 17 is a right side elevational view thereof;

FIG. 18 is a left side elevational view thereof;

FIG. 19 is a top perspective view of the second component of the slope adjustable head for pedestal jack of the present invention;

FIG. 20 is a bottom perspective view thereof;

FIG. 21 is a top plan view thereof;

FIG. 22 is a bottom plan view thereof;

FIG. 23 is a front elevational view thereof;

FIG. 24 is a rear elevational view thereof;

FIG. 25 is a right side elevational view thereof; and,

FIG. 26 is a left side elevational view thereof.

The second component is not shown in FIGS. 11 through 18 and the first component is not shown in FIGS. 19 through 26 for convenience of illustration.
